CORE BARREL ASSEMBLY

John C. Stokes, Houston, Tex., assignor to Reed
 Roller Bit Company, Houston, Tex., a corpora-
 tion of Texas

Application October 28, 1950, Serial No. 192,748

10 Claims. (Cl. 255—72)

1

This invention relates to new and useful improvements in core barrel assemblies.

As is well known, the usual core barrel assembly ordinarily comprises an outer barrel and an inner barrel, with a core catcher mounted in the lower portion of the inner barrel. The core being cut moves upwardly into the inner barrel past the core catcher and when the coring operation is completed, the engagement of the core catcher with the core is depended upon to effect fracturing or breaking off the core. Since the core catcher is mounted within the inner barrel, which must of necessity be rotatably connected to the outer barrel, the inner barrel carries the strain of breaking off the core. In the softer formations where breaking off of the core requires a relatively small force, little difficulty is experienced, but in the harder formations the strain occasioned by the breaking of the core may result in damaging the inner core barrel. Further, the usual core barrel assembly requires removal of the inner barrel from the lower end of the outer barrel which means that said inner barrel cannot be removed from the well bore separately from the outer barrel and this is disadvantageous if difficulty is encountered during the coring operation.

It is one object of this invention to provide an improved core barrel assembly which is particularly adapted for use in coring hard formations.

An important object is to provide an improved core barrel assembly wherein the core catcher is so mounted that when the core has been cut and the assembly moved upwardly to break off the core, the load imposed on the core catcher is transferred directly to the outer barrel of the assembly, whereby the inner barrel is relieved of the strain occasioned by breaking the core.

A particular object of the invention is to provide a core barrel assembly which includes a core catcher support slidably mounted on the lower portion of the inner barrel and adapted to support any selected type of core catcher; the construction being such that the catcher functions in a normal manner during the coring operation with a catcher support that may slide toward its upper position relative to the inner barrel, said support automatically moving downwardly into contact with the outer barrel assembly and core bit to transfer the strain of breaking the core to said outer barrel and bit when the assembly is lifted upon completion of the coring operation.

Another object of the invention is to provide a core barrel assembly which is so constructed that the inner barrel may be withdrawn from

2

the upper end of the outer barrel, whereby removal of the core from the barrel at the surface is facilitated and also whereby said inner barrel with catcher and core may be removed from the well bore separately from the outer barrel.

A still further object is to provide a core barrel assembly, of the character described, which is so designed that a safety joint may be connected between the inner barrel and the outer barrel of the assembly to permit separation of the inner barrel and removal thereof from the well bore independently of said outer barrel.

The construction designed to carry out the invention will be hereinafter described together with other features thereof.

The invention will be more readily understood from a reading of the following specification and by reference to the accompanying drawings forming a part thereof, wherein an example of the invention is shown, and wherein:

Figure 1 is a transverse, vertical sectional view of a core barrel assembly, constructed in accordance with the invention and illustrating the same in a position cutting the core.

Figure 2 is an enlarged transverse, sectional view of the lower portion of the assembly,

Figure 3 is a horizontal, cross-sectional view, taken on the line 3—3 of Figure 2,

Figure 4 is a horizontal, cross-sectional view, taken on the line 4—4 of Figure 2,

Figure 5 is a view, similar to Figure 2, illustrating the core-catcher support in position during breaking of the core,

Figure 6 is a sectional detail showing removal of the core from the inner barrel,

Figure 7 is a transverse sectional view of a modified form of the invention,

Figure 8 is a transverse sectional view of another modification of the invention,

Figure 9 is an enlarged sectional detail of the core catcher support shown in Figure 8, and

Figures 10 and 11 are horizontal, cross-sectional views, taken on the lines 10—10 and 11—11, respectively, of Figure 8.

In the drawings, the numeral 10 designates an outer tubular core barrel which has a core bit 11 connected to its lower end by means of a connecting sub 12. The core bit is formed with a central or axial opening 13 and is illustrated as the usual diamond type of core drilling bit. The central opening 13 in the bit is in axial alignment with an axial opening 14 in the sub 12; an annular inclined or beveled shoulder or seat 15 is formed within the sub 12 at the lower end 55 of the bore of said sub. The major portion of

the bore 12a of the sub is of a larger diameter than the bore 10a of the outer core barrel 10 to allow clearance and slush passage (Figure 5).

Adapted to extend axially through the outer core barrel 10 is an inner core receiving barrel 16, and said inner barrel is constructed of a suitable tube or pipe section. The upper end of the inner core receiving barrel has connection with a coupling assembly 17 and by means of the assembly 17 the inner core barrel is rotatably mounted within the bore 18 of a safety tool joint 19. The joint is provided with internal shoulders 20 and 21, which shoulders function to confine the coupling assembly 17 against longitudinal movement with respect to the joint 19, while permitting relative rotation of the joint with respect to the inner barrel 16. A short tube 22 surrounds the upper portion of the mandrel 17a of the coupling assembly 17 and extends into the lower end of an upper connection 23 which couples the safety joint 19 to the drill pipe (not shown). The tube 22 is retained in position by a retaining nut 22a. It is pointed out that any suitable type of rotatable mounting may be employed for connecting the upper portion of the inner core receiving barrel 16 to the joint 19. As will hereinafter appear, the relatively coarse thread 19a of the safety joint 19 could be omitted, and a standard thread substituted for the same.

The inner core receiving barrel 16 is axially aligned within the outer core barrel 10 by radial guide wings 24 secured to the upper end of the exterior of said inner barrel and said wings also function to guide the inner barrel during assembly. Obviously, the guides have an outer diameter which is less than the inner diameter of the outer barrel. The lower end of the barrel has a tubular sleeve member 25 threaded thereon, and this sleeve is also provided with centering wings 26 which maintain axial alignment of the lower end of the inner barrel. The lower portion of the sleeve member 25 is enlarged in diameter and is disposed within the bore 12a of the connecting sub 12; this enlarged lower portion of the member is formed with longitudinally extending slits which are spaced radially therearound to provide a plurality of resilient latching or stop arms 27. The inherent resiliency of the material of which the arms 27 are constructed normally maintains said arms in the position shown in Figure 2, but obviously said arms may be swung outwardly so that their lower ends may be spread in a radial direction. Each arm 27 is formed with an inwardly directed lug 28 at its extreme lower end.

An annular core-catcher support 29 is mounted within the lower portion of the sleeve member 25 and is axially slidable within limits within the latch arms 27. The support 29 is in the form of a collar and upward movement of this supporting collar is restricted by an internal shoulder 30 which is formed within the sleeve member 25 between the upper body portion of said sleeve and the latch or stop arms 27. Downward movement of the core-catcher support or collar 29 is limited by the engagement of a plurality of lugs 31 formed on the lower end of said collar with the inclined seat 15 provided within the lower end of the connecting sub 12. The lower surface of each stop lug 31 is beveled or inclined as indicated at 31a and this inclination is preferably complementary to the inclination of the seating surface 15. Complete displacement or downward movement of the core-catcher support or collar 29 from the sleeve mem-

ber 25, when said sleeve member and inner core barrel are outside of the outer core barrel, is prevented by the engagement of an external shoulder 32 formed on the support or collar 29 with the inwardly directed lugs 28 of the stop arms 27. Thus, when the inner core barrel is outside of the outer core barrel, downward movement of the support or collar 29 and displacement of this element from the sleeve member 25 is prevented by said shoulder 32 engaging the inwardly directed lugs 28 of the stop arms 27.

The bore 29a of the annular core-catcher support or collar 29 is tapered or inclined, as is clearly illustrated in Figure 2, and this tapered surface forms a seat for the usual split sleeve-type core catcher 33. It will be evident that as the core catcher moves downwardly along the tapered seat 29a, its inner diameter will be reduced to firmly engage a core which might be extending therethrough. The operation of the core catcher is usual and any suitable well known core catcher may be mounted within the support 29. Upward displacement of the core catcher 33 from the support 29 is prevented by means of a snap ring 34 which is mounted within the extreme upper end of the support or collar 29.

In the operation of the assembly, the parts are assembled as shown in Figure 1 and in such position the inner core barrel 16 is rotatably mounted within the safety joint 19. The relatively coarse threads 19a of the safety joint are coupled to the upper end of the outer core barrel 10 and since the upper end of the safety joint has connection through the upper connection 23 with the drill pipe (not shown) it will be evident that a rotation of the drill pipe will impart a rotation to the outer core barrel 10 and to the core drill 11 mounted at its lower end. As the core A is cut, it may enter the lower end of the inner core receiving barrel 16 in the usual manner, and said inner core barrel may remain stationary as the outer barrel and drill pipe are rotated.

As the coring operation proceeds, the frictional engagement of the core A moving upwardly through the opening 13 in the bit and then upwardly through the core catcher support 29 and core catcher 33 will cause the core catcher to ride upwardly within the support. At the same time, the support 29 will tend to be lifted to the upper position as shown in Figure 2, with the upper end of the support engaging the shoulder 30. At this time, the limiting or stop lugs 31 at the lower end of the support or collar 29 are spaced upwardly above the inclined seating surface 15 within the lower portion of the connecting sub 12.

When the coring operation is complete, rotation of the assembly is halted and an upward pull is taken on the drill pipe which tends to move the entire assembly upwardly. Because the core catcher 33 is in frictional engagement with the core A, which is at this time still attached to the formation, the upward movement of the assembly will tend to move the core catcher 33 downwardly along the tapered bore 29a of the core-catcher support 29. At the same time, the core-catcher support 29 will move downwardly until its stop or limiting lugs 31 engages the inclined seat 15 within the connecting sub, as shown in Figure 5. When this occurs, the strain which will be placed on the core catcher as a continued upward pull is taken on the drill pipe, is transmitted directly to the core-catcher support 29 and through the support to the connecting sub 12. The strain of breaking off the core is therefore

directly transferred to the bit 11 and outer core barrel 10, which parts are well capable of withstanding this strain because they are connected directly to the drill pipe. It is noted that because the core-catcher support 29 engages the seat 15 the inner core receiving barrel 16 is relieved of any possible strain which may be occasioned when the core is broken off. After breaking of the core, the entire assembly may be brought to the surface and the core catcher 33 will, of course, retain the core within the inner core receiving barrel in the usual manner.

After the assembly is brought to the surface, the inner barrel 16 may be removed from the outer barrel either by uncoupling the coarse threads 19a of the safety joint 19 to permit withdrawal of the inner barrel from the upper end of the outer barrel, or if desired the drill bit and sub may be removed from the lower end of the outer barrel so that the inner barrel may be withdrawn from the bottom of the outer barrel. In effecting the withdrawal from the bottom or lower end of the outer barrel the upper connection with the upper end of the safety joint 19 would, of course, have to be broken and the nut 22a and tube 22 removed from the inner barrel. The structure thus permits removal of the inner barrel from either the upper or the lower end, as desired, of the outer core barrel.

For permitting a removal of the core from the inner barrel, it is necessary that the stop arms 27 be spread to allow removal of the core-catcher support 29 and the core catcher 33 from the sleeve member 25. Spreading of the arms 27 may be accomplished in any suitable manner so as to permit the shoulder 32 on the core-catcher support 29 to clear the lugs 28, after which removal of the core-catcher support, together with the core catcher therein, from between said arms, is effected. To facilitate the spreading of the stop arms 27, a removal tool T illustrated in Figure 6 may be provided. This tool comprises a base 35 having an upstanding collar 36 secured thereto. The lower portion of the bore of the collar 36 has an inclined seat 37 which is disposed at an inclination complementary to the inclination of the lower end of the limiting or stop lugs 31 of the core-catcher support. The upper edge of the collar is beveled inwardly at 33, whereby said upper end may be engaged beneath the lower ends of the stop arms 27.

In using the tool T, the same is merely slid around the lower end of the core-catcher support 29 after said support and the inner barrel have been removed from the outer barrel, and the upper beveled end 38 of the collar 36 will engage beneath the arms 27 to move said arms radially outwardly. The collar 36 continues its inward movement on the core-catcher support until its inner end strikes the external shoulder 32 on said support and when this occurs the tool T and the support 29 may be removed from between the arms 27. Of course, the core catcher 33 within the support is still gripping the core and this will permit a removal of the core A from the inner core receiving barrel 16. Although the tool T illustrated in Figure 6 has been found satisfactory to effect a displacement of the core-catcher support from within the latch arms 27 of the sleeve member 25, any other desired method for spreading the latch arms to permit such displacement may be employed.

As has been noted, the drill pipe is connected to the outer barrel 10 through the safety joint 19. There may be instances where the drill bit and outer barrel 10 may become stuck within the

well bore during the coring operation, and if this occurs, the provision of the safety joint 19 will permit the drill pipe to be disconnected from the outer barrel. The inner barrel 16 is secured within the coupling 19, and this coupling has connection through regular threads with the drill pipe 23. It also has connection through the safety joint threads 19a with the outer barrel. The thread connection 19a is a coarser thread and when the drill pipe is turned in a left hand direction an unscrewing of the safety joint threads 19a will occur before unscrewing of the regular threads will take place. Therefore, if the outer barrel becomes stuck a rotation in a left hand direction of the drill pipe will break the connection at the threads 19a. Because the inner core receiving barrel 16 has its upper end connected with the safety joint 19, removal of the drill pipe after disconnection from the outer barrel will allow the inner barrel to be withdrawn upwardly with said drill pipe. This is a decided advantage because subsequent fishing operations in order to remove the stuck outer barrel will be greatly simplified when the inner barrel has been previously removed therefrom. The structure makes it possible to withdraw the inner barrel upwardly from the upper end of the outer barrel, and it is this arrangement which facilitates the use of a safety joint connection between the drill pipe and the outer barrel. Of course, it is to be understood that the invention is not to be limited to the use of the safety joint 19 because in those cases where it is not likely that the bit and outer barrel may become stuck, standard threaded connections may be used; however, the use of the safety joint 19 is of added protection in the event that sticking of the outer barrel should occur.

In Figure 7 a modified form of the invention is shown, and in this form the means which prevents complete displacement of the core catcher support from the lower end of the inner core barrel is varied. Referring to Figure 7, a core catcher support 29b is provided with an internal shoulder 29c at its upper end and said shoulder 45 confines the split core catcher 33 against upward displacement from said support. The upper portion of the support 29b is extended upwardly and telescopes a sleeve member 29d which is secured to and projects from the lower end of the inner core barrel 16. A connection between the upper portion of the support 29b and the sleeve 29d is effected by slots 29e formed in the support and pins 29f provided on the sleeve. It is evident that the pin and slot connection allows telescoping movement between the core-catcher support 29b and the sleeve 29d carried by the inner core barrel while preventing displacement of the support from said sleeve. The operation of this form of the device is identical to that of the first form heretofore described.

In Figures 1 to 6 the core catcher support is illustrated as employed with the usual diamond core bit, which, as is well known, is employed in extremely hard formations. It may be desirable in certain instances to employ the improved core-catcher support with an ordinary roller or soft formation type bit and in Figures 8 to 11, such an arrangement is shown.

Referring to Figure 8, the outer core barrel 10 has connection with the upper end of a roller type bit 40, which is threaded onto the lower end of said barrel. The bit 40 has an axial opening 41 extending therethrough and above said opening an internal annular shoulder 42 is provided. A tubular sleeve 43 which is somewhat similar

to the sleeve 25 of the first form is connected to the lower end of the inner core receiving barrel 16. The lower portion of the bore of the sleeve 43 is slightly enlarged to provide an internal shoulder 44 within the bore of said sleeve. An annular stop element 45 is threaded onto the lower end of the sleeve 43 and includes a collar portion 46 at its upper end and extends downwardly within the bore of the bit above the shoulder 42. A core-catcher support 48 in the form of a collar is slidable within the stop element 45 and is provided with an external shoulder 49 which co-acts with an inwardly directed shoulder 50 on the element 45 to prevent complete displacement of the support 48 from said stop element. A core catcher 51 which is shown as of the spring finger type is disposed within the sleeve 43 and has its lower end extending into the core-catcher support 48. The lower portions of the spring arms of the core catcher 51 are inclined to co-act with the tapered bore 48a of the support 48 so that upon downward movement the spring fingers of the catcher are more firmly engaged with the core extending therethrough. The lower end of the collar or support 48 is adapted to engage the internal shoulder 42 within the drill bit 40.

The operation of this form of the invention is substantially the same as the first form. As the core is cut and moves upwardly through the opening 41 in the bit and then through the annular core-catcher support 48 and core catcher 51, said core will tend to move the core catcher to its uppermost position engaging the restraining shoulder 44 within the sleeve 43. The support 48 for the core catcher may ride upwardly within the stop element 45 and thus, the coring operation proceeds in a normal manner.

When coring is complete and it is desired to break off the core, an upward pull on the drill pipe will tend to move the outer barrel and drill bit upwardly with respect to the core. Such upward movement will cause the shoulder 42 to engage the core-catcher support or collar 48 and will cause the collar to co-act with the lower ends of the core catcher to firmly grip the core. Subsequent upward pull on the drill pipe will transmit the strain of breaking off the core directly from the core through the core catcher and then through the core-catcher support 48 to the bit 40. Since the bit is attached to the outer core barrel 10 and then to the drill pipe, it is obvious that the drill pipe and outer barrel are well able to take the strain of breaking off a hard formation core. As in the first form of the invention, the inner core receiving barrel 16 is relieved of any of the strain of breaking off said core.

It is apparent that in the form shown in Figures 8 to 11, the safety joint 19 may be employed so as to permit removal of the inner core receiving barrel from the outer barrel through the upper end of said outer barrel, whereby in the event of sticking of the outer barrel and bit, the inner core receiving barrel may be removed with the drill pipe. Also, in this form of the invention, removal of the inner core receiving barrel may be effected from the lower end of the outer barrel by merely removing the drill bit 40 from the outer barrel and removing nut 22a and sleeve 22 from inner barrel. In all forms of the invention, the strain imposed upon the assembly due to breaking off of the hard formation core is transferred from the inner barrel directly to the drill bit and outer barrel, which latter parts

are more able to withstand said strain than is the inner barrel.

The foregoing disclosure and description of the invention is illustrative and explanatory thereof, and various changes in the size, shape and materials, as well as in the details of the illustrated construction may be made, within the scope of the claims, without departing from the spirit of the invention.

Having described the invention, I claim:

1. A core barrel assembly including, an outer barrel having an internal seat within its lower portion, an inner barrel within the outer barrel and having its lower end terminating above the seat, a sleeve member secured to the lower end of the inner barrel and having radially expansible elements on its lower end, an annular core catcher support slidable within the sleeve and confined against complete displacement downwardly therefrom by said radially expansible elements, the lower end of the support being engageable with the seat within the outer barrel prior to reaching its limit of downward movement relative to the expansible elements, and a core catcher mounted within the annular support.
2. A core barrel assembly as set forth in claim 1, wherein the annular support has a tapered bore and wherein portions of the external surface of the core catcher are also tapered, whereby downward movement of the catcher within the bore urges the catcher into tight engagement with a core extending therethrough and also sets up a frictional engagement between the catcher and its support.
3. As a sub-combination in a core barrel assembly, a core catcher unit comprising, a tubular sleeve having an internal shoulder therein and having radially expansible retaining elements extending downwardly below the shoulder, a core-catcher support slidably axially within the sleeve and having its inward movement limited by the shoulder and its outward movement limited by the retaining elements, and a core catcher mounted within the support.
4. The sub-combination set forth in claim 3, wherein the bore of the support is tapered and portions of the external surface of the core catcher are also tapered.
5. A core barrel assembly comprising, an outer barrel having an internal abutment at the lower end of its bore, an inner core-receiving barrel extending within the outer barrel and having its lower end terminating above the internal abutment, a core catcher support extending upwardly above the lower end of the inner barrel and having its downward movement limited by the engagement with the abutment, a lateral shoulder on said core catcher support, a lateral projection on said core-receiving barrel disposed below said lateral shoulder and being movable upwardly into engagement with said shoulder upon an upward movement of said core-receiving barrel relative to said support to thereby prevent separation of said support from said inner core-receiving barrel when said inner barrel is removed from said outer barrel, and a core catcher within the support and adapted to engage a core extending upwardly into the inner barrel, said catcher functioning to move the support downwardly into engagement with the abutment when the barrel assembly is moved upwardly relative to the core which is engaged by said core catcher, said lateral projection being spaced sufficiently below said lateral shoulder so that when said support is moved downwardly by said catcher the contact of

said support with said internal abutment prevents engagement of said projection with said shoulder.

6. The core barrel assembly as set forth in claim 5, wherein the bore of the core catcher support is tapered downwardly and inwardly and portions of the outer surface of the core catcher are also tapered downwardly and inwardly, whereby downward movement of the catcher relative to the support urges the catcher into tighter gripping engagement with the core and at the same time sets up a frictional contact between the catcher and the support to assure relative downward movement of the support with respect to the limiting abutment.

7. The core barrel as set forth in claim 5, wherein the outer barrel is connected to a drill pipe by means of a safety joint coupling and also wherein the inner barrel is attached to the coupling, whereby disconnection of said coupling from the outer barrel permits removal of the inner barrel upwardly from said outer barrel.

8. A core barrel assembly as set forth in claim 5, together with a pin and slot connection between the inner barrel and the core catcher support for permitting limited telescoping movement of the support relative to the barrel, while preventing complete separation of the support from said barrel.

9. A core barrel assembly including, an outer barrel, a safety joint coupling attached to the lower end of the drill pipe adapted to be coupled to the outer barrel, an inner core-receiving barrel having its upper end extending axially within the safety joint coupling, and a rotatable connection attaching said inner barrel to said coupling for relative rotation therebetween without separation of the inner barrel from the coupling

whereby said inner barrel may remain stationary when engaged by a core while the outer barrel and coupling are rotated, the safety coupling being releasable from the outer barrel while maintaining the connection between the coupling and the inner barrel whereby a core can be retrieved in the inner barrel even though the outer barrel is stuck in a well bore.

10. The core barrel assembly set forth in claim 9, wherein the safety joint coupling has an annular ledge of increased diameter as compared to its bore, said inner core-receiving barrel extending through the bore of the coupling and projecting above said annular ledge, and an annular flange on the external surface of said inner barrel and of larger diameter than the bore of the coupling and resting upon said annular ledge whereby the inner barrel is prevented from separating from the coupling upon upward movement of the coupling after disconnection from the outer barrel.
